UNITED STATES PATENT OFFICE

FLETCHER SCHAUM, OF PHILADELPHIA, PENNSYLVANIA, ASSIGNOR TO FLETCHER WORKS, OF PHILADELPHIA, PENNSYLVANIA, A CORPORATION OF PENNSYLVANIA

AUTOMATIC MACHINE-CONTROL MECHANISM

Application filed December 11, 1928. Serial No. 325,358.

This invention relates to an automatic machine control mechanism of the dobby card type and it consists in the novel features and arrangements hereinafter described and 5 claimed.

An object of the invention is to provide mechanism of the character stated which is strong and rugged, of compact assemblage, occupying but small space and adapted to 10 be used in conjunction with looms, batch mixing apparatus or other similar machines and provides means for automatically throwing into action or operating the several instrumentalities of the machine or apparatus, so 15 that the said instrumentalities may function in proper order and in prescribed timed relation and in accord with predetermined rhythm of procedure.

A further object of the invention is to 20 provide an automatic control mechanism, simulating the mechanism usually employed in a dobby card loom for actuating hooks, needles and knives, the distinction being that the arrangement is such that the knives and 25 needles are dispensed with and the instrumentalities of the machine or apparatus which is controlled are actuated by lugs carried by the cards, the said cards being mounted for movement around a shaft and for 30 reciprocation in order to present them successively and in proper sequence to active position.

With these and other objects in view the machine control mechanism includes in combination with other elements and features a 35 series of dobby cards similar to those used in a loom. The cards are linked together in the form of an endless belt or chain and the chain is mounted for movement in an orbital path, 40 means are provided for shifting the chain bodily at regular intervals of time, so that the card of the chain which is at the active point in the orbit will present its lugs to the lug of a certain bar of a set, whereby the card 45 and the bar are moved concurrently and operate the instrumentality of the machine with which the bar is connected. At the same time there will be no movement of the bars which are not to be operated because the lugs co- 50 inciding with these bars are omitted when

it is desired not to operate those particular bars.

When the cards are assembled in the form of a chain and connected together they may be arranged to vary the sequence of operation 55 of the bars, to vary the order of operation thereof and to vary the intervals of duration or extent of the periods of inactivity therefor, or to operate more than one bar at one time. 60

In the accompanying drawings:—

Fig. 1 is a plan view of the automatic machine control mechanism,

Fig. 2 is a longitudinal sectional view there- 65 of cut on the line 2—2 of Fig. 1 and showing the bar lugs in a normal position,

Fig. 3 is a longitudinal sectional view cut on the line 3—3 of Fig. 1 and showing the lug 70 of the dobby card in the act of striking the lug of one of the bars and actuating the same,

Fig. 4 is a view taken on line 4—4 of Fig. 1, the parts being shifted however to illustrate the beginning movement of the cylinder, 75

Fig. 5 is a detail view showing the cylinder approaching its outermost position, and

Fig. 6 is a detail view showing the cylinder in its outermost position.

The automatic machine control mechanism is mounted upon a supporting base 1. This 80 base may be the frame of a loom, a batch mixing apparatus, or any other machine or apparatus with which the control mechanism is used.

Standards 2 are mounted upon the base 1 85 and a shaft 3 is journaled for rotation in the upper ends of the standards and bridges the space between the standards.

A pulley wheel 4 is fixed to one end of the shaft 3 and a belt 5 is trained around the 90 pulley wheel and is adapted to rotate the said wheel and the shaft. Any other suitable means may be provided for rotating the shaft 3.

Eccentrics 6 are mounted upon the shaft 3 95 at points between the standards 2 and are spaced from each other. The bases of the standards 2 are provided with slots 7 and bolts 8 pass through the said slots and are screwed into the supporting base 1. By 100

loosening the bolts 8, the standards may be shifted along the supporting base 1 and when the standards are adjusted they are fixed or secured by tightening the bolts 8.

5 Frame sides 9 are mounted upon the supporting base 1 and are disposed parallel with relation to each other. Guide members 10 and 11 are mounted upon the base 1 and are disposed transversely of the frame sides 9 and in the vicinity of the ends thereof.

The frame sides 9 are provided at their upper portions with recesses 12, upon the lower edges of which are mounted guide strips 13.

15 A shaft 14 is provided with cylindrical end portions 15 which ride upon the guide strips 13. The end extremities of the shaft 14 are journaled in pitmen bars 16 and the said bars are provided with eccentric straps 17 which

20 surround the eccentrics 6.

As the shaft 3 rotates the eccentrics 6 are carried around the axis thereof and through the straps 17 the pitmen bars 16 are reciprocated and the shaft 14 and the cylindrical portions 15 thereof are caused to slide along the guide strips 13. The cylindrical portions 15 are provided at their outer ends with angular flanges 18 which move along the side edges of the guide strips 13 and hold the 25 shaft 14 parallel with the shaft 3. The flanges 18 are provided with radially projecting rounded corners 19.

Dogs 20 are pivotally mounted at the sides of the frame member 9 and are provided at 35 their upper edges with hooks 21 which are normally held in the path of movement of the corners 19 by flat springs 22 also mounted upon the frame sides 9 and which bear at their free ends against the lower edges of the 40 dogs 20.

When the shaft 14 is moved away from the corners 21 and the cylindrical portions 15 slide upon the guide plates 13 as hereinbefore stated, and when the shaft 14 is moved 45 toward the hooks 21 and one of the corners 19 comes in contact with the hooks, the peripheral portions of the cylinders 15 are arrested while at the same time the axis of the shaft 14 is moved over and beyond the hooks 21, thus the shaft 14 in its reciprocatory movement is given a turn or partial rotation at the end of the stroke. Rods 23 are pivotally connected at one end with the frame sides 9 and are provided on their 55 under sides with friction plates 24 which rest upon the edges of the uppermost rounded corners 19 of the flanges 18 as shown in Figs. 2 and 3 of the drawing.

Traction springs 25 are connected at one 60 end with the free end of the rods 23 and connected at their other ends by means of links 26 with the supporting base 1. Thus the plates 24 are held resiliently in contact with the uppermost corners 19 of the flanges and the shaft 14 is restrained against turning or

rotary movement until such time as one of the corners 19 comes in contact with the hooks 21 when the said shaft is partially turned as hereinbefore described.

The intermediate portion 28 of the cylinder shaft 14 is provided with angularly disposed faces 27, best shown in Figs. 2 and 3 of the drawings. The shaft is further provided in the vicinity of the ends of the faces thereof with outstanding studs 29. A yoke 30 is pivotally mounted upon the base 1 and a roller 31 is journaled between the upper ends of the arms of the said yoke.

70 A spring 32 is connected at one end with the intermediate portion of the yoke and at its other end with the supporting base 1. The spring 32 is under tension and with a tendency to hold the roller 31 spaced away from the shaft 14.

80 A series of dobby cards 33 are connected together by means of links 34 whereby the said series of cards form an endless chain or belt which is trained around the roller 31 and the intermediate portion 28 of the shaft 14. Certain of the cards 33 are provided at 85 their outer faces with transversely disposed out-standing shoulder lugs 35 and with stud receiving openings 36. The said openings 36 are adapted to receive certain of the studs 29 as the card is moved around the axis of the shaft 14. Some of the cards are devoid of lugs so that the cycle of operation will not be interrupted until desired.

90 All of the cards are of the same length, breadth and thickness and the length and breadth of each card is substantially the same as the length and breadth of each of the faces 27 of the shaft 14. Because the roller 31 is held away from the shaft 14 by the spring 32 and inasmuch as the chain of cards is trained 95 around the roller 31 and the shaft 14, the upper and lower runs of the chain of cards are maintained in proper taut condition.

100 Bars 37 are mounted for sliding movement in the guide members 10 and 11 and are provided with stop pins 38. Coil springs 39 are connected at one end with the bars and at their other ends with a rail 39' supported upon the base 1. The springs 39 are under tension with a tendency to hold the stop pins 38 against the side of the guide member 11 and the bars at normal position.

110 Levers 40 are pivotally mounted upon the supporting base 1, one of them being located in alignment with each of the bars 37. Links 120 41 connect the aligned rods and levers together. The levers 40 are provided at their outer edges with rows of notches 42 and said notches are adapted to receive pull elements 43, which are connected with the throwing-in mechanisms of the machine (not shown) and to which a control mechanism is applied. Each of the bars 37 is provided at a point between its ends with an up-standing lug 44. The lugs 44 are located between the guide 125 130

members 10 and 11 and the upper edges of the lugs 44 overlap the plane in which the lower edges of the lugs 35 lie, when the actuating card is disposed directly at the underside of the shaft 14. Thus the said lugs overlap

- 5 each other in a plane lying between the plane of movement of the bars and the plane of reciprocatory movement of the lugs of the card located directly under the shaft 14. As the shaft 14 is reciprocated, the chain of cards 10 is correspondingly moved and when the shaft arrives at the outer end of its stroke, it is turned as hereinbefore described, so that a new card is brought to position immediately below the axis of the shaft 14. As the shaft 15 14 moves toward the bar lugs 44, the shoulder lug 35 of that card which is immediately below the axis of the shaft 14, strikes one of the lugs 44 and carries the bar to which the said lug 44 is attached, along with the shaft 20 14. The bar or bars which are moved, swing those levers 40 which are connected thereto by means of their respective links 41. As the said levers are swung they move the pull elements 43 connected thereto and thus the 25 instrumentalities of the machine to which the control is applied will be thrown into action or operation.

It is obvious by varying the arrangement of the cards in the chain and by varying the 30 location of the shoulders upon the cards, that the instrumentalities of the machine to which the device is applied may be thrown into action at the desired intervals and that the extent of the operation or action of such instrumentalities may be controlled so that desired 35 cycles of action may be had to bring about the required results in the machine that is being controlled.

The cards may be arranged to vary the sequence of operation of the bars, to vary the order of operation thereof and to vary the intervals of duration of activity or the periods of inactivity thereof.

From the foregoing it will be seen that I 45 have produced an automatic control mechanism wherein a number of parts that are necessary in the original form of dobby mechanism are dispensed with.

It will also be seen that the movement of 50 the shaft that carries the cards directly actuates the bars that are selectively operated by certain cards. Thus I dispense with needles and actuating hooks which are usually employed in looms.

It will also be seen that the force is transmitted from the cards moving in one plane to the bars moving in a parallel plane through the instrumentality of lugs carried by the 60 cards and bars and which have edge portions over-lapping each other in a plane lying between the plane of movement of the cards and the bars.

When it is desired not to operate any of 65 the bars 37 the card or cards devoid of the

lugs are used and they move over the tops of the lugs upon the bars and consequently the bars are not operated and there will be no change in the cycle of operation of the machine.

The control has proven extremely efficient in service and as will be understood is very easy to assemble, relatively cheap to manufacture and is of compact nature.

It will be understood that changes or variations may be made in the arrangement, without departing from the spirit of the invention as expressed in the claims.

Having thus described my invention, what I claim as new and desire to secure by Letters 80 Patent is:—

1. An automatic control comprising a series of slidable elements respectively connected with the instrumentalities to be controlled and a series of predeterminedly arranged elements mounted for movement in an orbital path having a section disposed parallel with the plane of movement of the slidable elements, said slidable and movable elements having shoulder lugs, the edges of which overlap each other at said section of parallelism and adapted to have contact to slide certain of the slidable elements concurrently with the movable elements to actuate the control and means for reciprocating the series of elements. 95

2. An automatic control comprising a pair of series of slidable and movable elements mounted for reciprocatory movement in parallelism along a section of the path of travel, the members of both series having shoulder lugs, the edge portions of which overlap each other at said section of parallelism and in a plane lying between said series and means for moving one of the series of elements to bring the lugs thereof in contact with the lugs of certain of the elements of the other series of elements to move the same concurrently to actuate the control. 105

3. An automatic control comprising a series of bars connected with the instrumentalities 110 to be controlled, said bars being mounted for sliding movement in a plane, said bars having portions disposed out of said plane, a series of cards mounted for reciprocatory movement and having a card at active position and moving while at said position in a plane parallel with the plane of movement of the bars and spaced therefrom, the card at active position having a portion disposed out of the plane of movement thereof and adapted 115 to engage directly said portion disposed out of the plane of movement of the bars to move the bar having said portion and actuate the control. 120

4. An automatic control comprising a series 125 of bars connected with the instrumentalities to be controlled, said bars being mounted for sliding movement in a plane, the bars having lugs located between their ends, a series of cards mounted for reciprocatory movement 130

- and having a card at active position and moving while at said position in a plane parallel with the plane of movement of the bars and spaced therefrom, the card at active position
5 having a portion adapted to engage directly the lug of a certain bar at a point lying in a plane located between the planes of movement of the bars and the active card, to move said bar and actuate the control.
10 5. An automatic control comprising a series of bars connected with the instrumentalities to be controlled, said bars being mounted for sliding movement in a plane, the bars having lugs located between their ends, a series of
15 cards mounted for reciprocatory movement and having one of the cards at active position and moving while at said position in a plane parallel with the plane of movement of the bars and spaced therefrom, the card at active position having a lug adapted to engage the lug of a certain bar at a point lying in a plane located between the planes of movement of the bars and the active card to move said bar concurrently and actuate the control.
20 25. In testimony whereof I affix my signature.
FLETCHER SCHÄUM.
